UNITED STATES PATENT OFFICE.

FRANKLIN TRUMAN DAVIS, OF MOUNT VERNON, NEW YORK.

SASH-FASTENER.

1,127,200.

Specification of Letters Patent. Patented Feb. 2, 1915.

Application filed June 4, 1914. Serial No. 842,913.

To all whom it may concern:

Be it known that I, FRANKLIN T. DAVIS, a citizen of the United States, and a resident of Mount Vernon, in the county of West-
5 chester and State of New York, have invented a new and Improved Sash-Fastener, of which the following is a full, clear, and exact description.

My invention relates to sash fasteners; 10 and the object thereof is to provide a simple, inexpensive and automatic sash fastener which is burglar-proof, and which fastener will automatically close only when the two sashes of a window are moved to the closed 15 position, whereby injury is prevented to the window by the fastener.

With the above and other objects in view, the nature of which will more fully appear as the description proceeds, the invention 20 consists in the novel construction, combination and arrangement of parts as herein fully described, illustrated and claimed.

In the accompanying drawings, forming part of the application, similar characters 25 of reference indicate corresponding parts in all the views, and Figure 1 is a plan view of a fastener embodying my invention showing it as applied to sashes in closed position; Fig. 2 is a vertical section on line 30 2-2, Fig. 1; Fig. 3 is a side elevation of the fastener showing the same in open position with the sashes relatively displaced; Fig. 4 is a section similar to Fig. 2 showing the sash fastener locking the sashes at a slightly 35 different position than what is shown in Fig. 2; Fig. 5 is a plan view of the base-plate showing a modified structure of the catch; and Fig. 6 is a plan view of a modified structure of the dog adapted to engage 40 the catch.

Before proceeding to a more detailed description of my invention, it must be clearly understood that my fastener herein disclosed is an improvement over my Patent No. 45 331,041.

The improvement in the fastener herein described consists in the provision of a dog which retains the latch of the fastener in the open position and of a trigger associated 50 with the dog permitting the release of the latch from the open position, only when the latch and catch therefor of the fastener are moving toward one another.

Referring to the drawings, more particularly to Figs. 1 to 4, inclusive, 7 represents a base-plate having means whereby the same

may be secured in a suitable place to the upper sash. Spaced lugs 8 are provided at the interior side of the base plate, and pivotally mounted therebetween is a latch 9. 60 The latch has an elongated slot 10 open at the pivoted end. A portion 11 bridges the lower surface of the said slot adjacent the pivoted end; the purpose of the portion 11 will appear hereinafter. The pin 12 which 65 connects the latch to the base-plate 7 carries a spring 13 which normally tends to force the latch from the open to the closed position, *i. e.*, from the position shown in Fig. 3 to the position shown in Fig. 2. Pivotally 70 mounted in the slot 10 above the bridged portion 11 is a dog 14 provided at the non-pivoted end with an opening 15, preferably rectangular in shape, which is adapted to engage a hooked end 16 of a stop 17 forming 75 an integral part of the base-plate 7. The dog 14, at the non-pivoted end, is also provided with a downward projection 18 which rests against the back of the stop 17 under the action of the spring 13 when the 80 latch is in the open position. To prevent the projection 18 of the dog 14 from maintaining its engagement with the rear of the stop 17 when the latch 9 is moved toward the stop, said stop is provided with shoulders 85 19 on which the non-pivoted end of the dog rests when the latch is in the open position. The dog 14 at the pivoted end is provided with a slot 20; and mounted in the slot on a pivot 21, which connects the dog to the 90 latch, is a trigger 22 the end 23 of which normally projects out of the slot 20 and which end is heavy enough to always bring the other end 24 of the trigger against the bottom of the slot 20. 95

Secured to the lower sash is a catch 25 which is adapted to project through the slot 10 adjacent the dog 14, the catch 25 being provided with a suitable base-plate 26 which is provided with means for securing the same 100 to the lower sash. The opening 15 and the projection 18 of the dog 14 are so formed with reference to the stop 17 that when the dog 14 is in engagement with the stop 17 the lower surface of the latch 9 overhangs 105 the inner side of the base-plate 7, as best seen in Fig. 3. This is done for the purpose of causing the disengagement of the dog 14 from the stop 17 when the projecting part 27 of the latch comes in contact with the 110 transverse part of the lower sash which carries the catch 25.

It will be seen from Fig. 3 that as the lower sash moves downward in the direction of the arrow as shown, or the upper sash upward, the latch 9 will be moved toward the upper sash, moving therewith the dog 14, as shown in Fig. 3 in dotted line, until the upper edge of the sash strikes the end 23 of the trigger 22, which will raise the dog 14 above the stop 17 and permit the downward movement of the latch 9 as the upper sash passes said latch and arrives at the position shown in Fig. 2 or Fig. 4.

The upper surface 28 of the stop 17 is so formed that its engagement with the projection 18 of the dog 14 prevents interference between the catch 25 and the end 23 of the trigger by keeping the said end of the trigger clear of the catch. Furthermore, the upper boss 29 of the dog 14 prevents the said dog from passing through the slot 10, as the distance of said boss 29 from the pivot 21 is greater than the distance of the upper edge of said slot 10 from the said pivot. If the said dog should be thrown against the upper edge of the slot 10 in the downward movement of said latch, the catch 25 will move the same into the position shown in Figs. 2 and 4.

From the above description it will be seen that the latch 9 will engage the catch 25 automatically when the catch or latch are moved toward each other. To disengage the latch 9 from the catch 25 the dog 14 is moved on its pivot 21 by applying a slight pressure to the boss 29, thereby disengaging the projection 18 of the dog from the shoulders 30 or 31 (see Figs. 2 and 4) of the stop 17 and then moving the latch 9 on its pivot until the hook 16 catches the dog as previously described. After the latch has been placed into position shown in Fig. 3, while the sashes are in the position shown in Fig. 2, and the lower sash or the upper sash is moved relative to one another, the upper edge of the lower sash will come in engagement with the end 23 of the trigger 22, moving the same upwardly. The end 24 of the trigger 22 by this movement is cleared from the bottom of the notch 20 in the dog, leaving the dog in engagement with the stop 17 until the projecting part 27 of the latch 9 is engaged by the said edge of the window, when the dog 14 will be moved away from the stop 17, as previously stated. Due to the fact that the action of gravity on the dog 14 always tends to keep the same in engagement with the stop 17, the movement of the latch on its pivot will only move said dog on the shoulders 19 until the lower sash releases the latch 9, which will bring the projection 18 against the rear of the stop, and the hook will prevent the snapping of said dog from the stop no matter how fast the latch 9 moves on its pivot. From the above it will be seen that the latch 9 can

only be released from the stop when the catch is moved toward the latch or vice versa. Therefore, under no circumstances can the latch 9 break the window carried by the lower sash, as generally happens.

The reason for providing the upper shoulder 31 on the stop 17 is to permit the locking of the window when dirt, snow or ice accumulates below the lower sash. The provision of the bridging portion 11 is to prevent the raising of the dog 14 from the position shown in Figs. 2 and 3 by inserting a wire between the sashes, as is generally done by burglars; so that this bridging portion in the latch makes the same burglar proof.

In Figs. 5 and 6 a modified structure of the stop and dog is illustrated. In this case the dog 14', at the non-pivoted end, is provided with notches 32 at the sides thereof in lieu of the opening 15, and, therefore, the non-pivoted end is T shaped, as shown at 33. The stop 17' in this case is provided with a slot, the sides 34 of which slot has a hooked end adapted to be engaged by the T 33 so that ultimately the same result is obtained. The pivoted end of the dog 14' is provided also with a trigger 22', which is similarly operated.

From the foregoing description, taken in connection with the accompanying drawings, the advantage of the construction and operation of the device shown will be readily understood by those skilled in the art to which the invention pertains; and while I have described the principle of operation, together with the device which I now consider to be the best embodiment thereof, I desire to have it understood that the device shown is merely illustrative and that such changes may be made when desired as are within the scope of the appended claims.

Having thus described my invention, I claim as new and desire to secure by Letters Patent:

1. In a fastening device of the class described, a base plate, a latch associated therewith, a catch, a dog carried by the latch co-acting with the base plate for locking the latch in open or closed position, and a trigger carried by the dog whereby said latch can only be released from its open position when the latch is moved toward the catch or the catch toward the latch.

2. In a fastening device of the class described, a base-plate having a stop thereon, a spring actuated latch pivotally connected to said base-plate, a catch for said latch, a dog pivotally connected to said latch, said stop having a hook adapted to engage the dog whereby said latch is locked in open position, and a trigger associated with the dog for raising said dog above the hook after the dog has been moved by the latch to clear the hook, said trigger operating the

dog when said latch is moved toward the catch or the catch, toward the latch, said stop having means adapted to be engaged by said dog when said latch engages the catch, whereby said latch is locked in closed position.

3. In a fastening device of the class described, a base-plate having a stop thereon; a spring-actuated latch pivotally connected to said base-plate, said spring normally tending to move said latch to the closed position; a catch for said latch, said latch having a slot adapted to engage the catch when said latch is in closed position; a dog in said slot pivotally connected to said latch, said stop having a hook adapted to engage the dog, whereby said latch is locked in open position; and a trigger associated with the dog for raising said dog above the hook, 20 said latch overhanging said base-plate when locked in open position, so that when the catch or latch moves relatively to each other said latch is moved on its pivot, whereby the dog is moved by the latch to clear the hook, the said trigger being adapted to operate the dog on its pivot when the latch is moved toward the catch or the catch, toward the latch.

4. In a fastening device of the class described, a base-plate having a stop thereon; a spring-actuated latch pivotally connected to said base-plate; a catch for said latch; a dog pivotally connected to said latch and adapted to engage said stop, whereby said latch is locked in open or closed position; means associated with the dog for unlocking the latch when the same is locked in open position, said means becoming operable when said latch moves toward the catch or 30 the catch, toward the latch, said latch having means preventing an unauthorized displacement of the dog when the latch is locked in the closed position by said dog.

5. In a fastening device of the class described, a base-plate having a stop thereon; a spring actuated latch pivotally connected to said base-plate; a catch for said latch;

and a dog pivotally connected to said latch and adapted to lock said latch in open or closed position, said stop having means 50 whereby said latch can be locked in closed position in predetermined places, substantially as and for the purpose set forth.

6. In a fastening device of the class described, a base-plate having a stop thereon; a spring-actuated latch pivotally connected to said base; a catch for said latch; and a dog pivotally connected to said latch and adapted to engage said stop, whereby said latch is locked by said dog in open or closed 55 position in predetermined places, standers adapted to be engaged by said dog when said latch is in closed position, whereby said latch can be locked in two different closed positions, substantially as and for the pur- 60 pose set forth.

7. In a fastening device of the class described, a base plate, a latch movable thereon, a catch for the latch, means carried by the latch adapted to engage the base plate 70 for locking the latch in open or in closed position, and a trigger carried by said means adapted to release said latch from the open locked position when said latch is moved toward the catch or the catch, to- 75 ward the latch.

8. In a fastening device of the class described, a base plate, a latch mounted to swing on the plate, a catch for the latch, a dog on said latch adapted to co-act with 80 the base plate to lock said latch in open position, and a trigger carried by said dog for moving the dog on its pivot when said latch is in open position and said latch moves toward the catch or the catch, toward the 85 latch.

In testimony whereof I have signed my name to this specification in the presence of two subscribing witnesses.

FRANKLIN TRUMAN DAVIS.
